CLAIM

The ornamental design for a cartridge for medicine injector, as shown and described.

DESCRIPTION

FIG. 1 is a front perspective view of a cartridge for medicine injector of the present invention, showing a cap attached thereon;

FIG. 2 is a rear perspective view thereof, showing the cap attached thereon;

FIG. 3 is a front perspective view thereof, dispensing with the cap;

FIG. 4 is a front view thereof, showing the cap attached thereon;

FIG. 5 is a rear side view thereof, showing the cap attached thereon;

FIG. 6 is a left side view thereof, showing the cap attached thereon;

FIG. 7 is a right side view thereof, showing the cap attached thereon;

FIG. 8 is a top view thereof, showing the cap attached thereon; and,

FIG. 9 is a bottom view thereof, showing the cap attached thereon.

The broken lines depict portions of the cartridge for medicine injector in which the design is embodied that form no part of the claimed design. Additionally, the dash-dot lines denote the boundary of the claim and form no part of the claimed design.

1 Claim, 3 Drawing Sheets
